CLAIM

I claim the ornamental design for a gun rest, substantially as shown and described herein.

DESCRIPTION

The present invention relates to the aesthetic features of a gun rest device for use with a support structure such as a walking staff or tripod.

FIG. 1 is a perspective view of a gun rest in accordance with the present invention;

FIG. 2 is a front side elevation view thereof, the back side elevation view is the same;

FIG. 3 is a top plan view thereof;

FIG. 4 is a bottom plan view thereof; and,

FIG. 5 is a right side elevation view thereof, the left side elevation view is the same.
